UNITED STATES PATENT OFFICE

146,556

DESIGN FOR AN ELECTRIC LAMP STAND OR THE LIKE

James F. Chamness, Dwight, Ill.

Application October 19, 1945, Serial No. 123,012

Term of patent 3½ years

(Cl. D48—20)

To all whom it may concern:

Be it known that I, James F. Chamness, a citizen of the United States, and residing at Dwight, county of Livingston, and State of Illinois, have invented a new, original, and ornamental Design for an Electric Lamp Stand or the like, of which the following is a specification, reference being made to the accompanying drawings, forming a part thereof.

Fig. 1 is a side view in elevation of the electric lamp stand or the like showing my design;

Fig. 2 is an end view in elevation thereof;

Fig. 3 is a top plan view of the same.

The dominant features of my design reside in the portions shown in full lines.

I claim:

The ornamental design for an electric lamp stand or the like, as shown and described.

JAMES F. CHAMNESS.
